UNITED STATES PATENT OFFICE.

CHARLES A. CARLSON, OF CHICAGO, ILLINOIS, ASSIGNOR TO HERBERT B. MUNSEY, OF CHICAGO, ILLINOIS.

LOOSE-LEAF BINDER.

SPECIFICATION forming part of Letters Patent No. 787,353, dated April 18, 1905.

Application filed June 24, 1904. Serial No. 214,016. (Model.)

To all whom it may concern:

Be it known that I, CHARLES A. CARLSON, a citizen of the United States, residing at Chicago, in the county of Cook and State of Illinois, have invented certain new and useful Improvements in Loose-Leaf Binders, of which the following is a specification.

My invention relates to that class of loose-leaf binders having a pair of side binder-frames 10 movable in opposite directions transversely with relation to each other, binder-pins upon such side binder-frames, crossed levers pivotally connected together at their longitudinal center and having their ends pivotally connected with such side binder-frames, and means for operating such levers, and thereby the side binder-frames.

The principal object of my invention is to provide a simple, economical, and efficient 20 file-binder.

A further object of the invention is to provide a file-binder having side frames provided with binder-pin mechanism thereon with simple and efficient lever mechanism for moving 25 such side binder-frames back and forth with relation to each other and with suitable, simple, and efficient means for operating such lever mechanism, and thereby the side binder-frames.

30 A further object of the invention is to provide a loose or changeable leaf binder with a suitable back and simple and efficient screw and lever mechanism for operating the side binder-frames and back portions.

35 The invention relates particularly to the lever mechanism for operating the side frames and to the means for operating such lever mechanism, and thereby the side frames.

The invention consists in the features, combinations, and details of construction herein- 40 after described and claimed.

In the accompanying drawings, Figure 1 is a plan view of a loose-leaf binder constructed in accordance with my improvements; Fig. 2, 45 a broken longitudinal sectional elevation taken on line 2 of Fig. 1 looking in the direction of the arrow, showing the relative positions of the binder-pins and guides and of the operating-lever and back portions; and Fig. 3 a 1 transverse sectional elevation of the binder- 50 frame, taken on line 3 of Fig. 1 looking in the direction of the arrow and showing such frame provided with the side cover-leaves and one manner of attaching such cover-leaves to the metallic portions of the frame. 55

In constructing a loose-leaf binder in accordance with my improvements I provide a pair of metallic side binder-frames *a*, upon which are mounted telescopic binder-pins formed of outer tubular portions *c* and inner 60 pin portions *b*, which are slidably mounted in such tubular portions so as to form telescopic or collapsing binder-pin mechanism adapted to hold suitably-slotted loose leaves 65 interchangeably in position upon such binder-pins and between the side frames. In order to permit loose leaves to be readily removed, interchanged, or new ones to be placed in position, it is desirable that simple and economical means be provided for operating or expanding and collapsing the binder-frame by 70 moving such side frames backward and forward transversely in opposite directions with relation to each other. In order to accomplish this, a pair of side frame-operating levers *d* are arranged in crossed relation to each other and pivoted at their longitudinal center upon a connecting pivot pin or screw *e*, such levers being pivotally mounted upon the side frames by means of studs *f*, having suitable 75 horizontal slots for receiving the swinging ends of the levers and having pivots *g*, which extend through elongated slots *h* in such levers, and thereby hold them in place. A sliding movement of the levers is thus permitted 80 with relation to the studs and side binder-frames and also a pivotal movement upon such pivot-pins. In order to provide suitable means for operating such levers, and thereby the side binder-frames, I mount a pair of depending studs or posts *i* pivotally, one upon 85 each of such levers, at equal distances from the point where such levers are pivotally connected together. The upper ends *j* of the studs are headed sufficiently to hold them pivotally in position upon the levers, which may be provided with suitable bearings *k*. One 90 of these studs is provided with a transverse

perforation having right-hand screw-threads and the other with a similar perforation having left-hand screw-threads arranged in alignment with each other at right angles to the 5 side frames. A screw l , having right and left screw-threads m and n upon its opposite ends, is mounted in the correspondingly-threaded perforations in such depending studs or posts, so that the rotation of such screw in one direction will cause the posts, and with them the 10 ends of the levers upon which they are mounted, to move apart, and turning it in the opposite direction will cause them to move toward each other. To enable the screw, and thereby 15 the levers and side frames, to be readily operated, such screw is provided with a squared end o , adapted to engage a correspondingly-shaped socket in the end of a key p , which is inserted through an opening q in one of the 20 side binder-frames provided for the reception of such key.

A suitable telescopic back r is provided in the form of two relatively movable portions s and t of metal riveted to the side binder-frames at or near their lower edges, such metallic portions of the back being provided with suitable canvas or leather coverings u . Suitable side cover-leaves v are flexibly connected with the side frames by means of flexible coverings w , formed of canvas or leather, an inner lap of which extends on the inside of the metallic portion of the corresponding side binder-frame and the outer lap y of which extends on the outside of the side binder-frame and preferably covers the metallic portion of the back, which is attached to such side binder-frame. Each of the relatively movable portions of the back is provided at each end with an upwardly-extending inclosing flange or end portion z , which may be covered with leather, if desired, and which protects the ends of the leaves and produces a finished appearance.

The telescopic binder-pins serve in a great 45 measure to guide the side binder-frames in their transverse movements, produced by the operation of the levers, and to hold such side binder-frames in the desired position longitudinally with relation to each other. When 50 the back portions are attached to the side binder-frames, as here shown, they also serve to guide the side binder-frames; but in order to secure rigidity of the binder against the torsional or twisting strains to which it is 55 subjected in use I provide guides which will insure the free transverse movements of the side frames in opposite directions. These guides are formed of tubes 2, mounted upon one of such side binder-frames preferably beneath the level of the operating-levers, and 60 guide-pins 3, mounted upon the opposite side binder-frame and extending slidably into the axial opening in such tubes, so as to form telescopic guides for guiding the side binder-frames and preventing undue play thereof.

By the above arrangement it will be seen that a changeable or loose-leaf binder is provided having operating-lever mechanism of the simplest possible character for moving the side frames, and thereby the telescopic 70 back portions, in opposite directions transversely and that a very simple and economical means for operating such levers, comprising a screw l , with its right and left screw-threads in threaded engagement with the pivotal studs 75 or posts in the levers, is thus provided. The mechanism thus provided is of the simplest possible construction and has the advantages of being not liable to get out of order, easy to repair, and efficient in operation. The 80 screw is by the simplest possible means mounted upon and connected with the levers, so that turning it in either direction will produce a corresponding movement of the levers, and thereby open and close the relatively 85 movable binder mechanisms, which I here designate as "side binder-frames."

I claim—

1. In a mechanism of the class described, the combination of a binding means comprising 90 two relatively movable members, crossed levers having their ends operatively connected to such side members and provided with means for engaging a screw, and a screw operatively connected with such levers for oscillating them 95 and thereby operating the side members, substantially as described.

2. In a mechanism of the class described, the combination of a binding means comprising 100 two relatively movable side members, crossed levers pivoted at their longitudinal centers having their ends operatively connected with such side members, a back connected with the side members, and a screw operatively connected with such levers for operating them 105 and thereby the side members, substantially as described.

3. In a loose-leaf binder, the combination of 110 a pair of side binder-frames provided with binder-pin mechanism thereon, crossed levers pivoted together and having their ends operatively connected with such side binder-frames, and a screw operatively connected with such levers for operating them and thereby the side binder-frames, substantially as described.

4. In a loose-leaf binder, the combination of 120 a pair of side binder-frames, a pair of levers pivotally connected together each having one end connected with each of such side binder-frames, a screw mounted between such side binder-frames, and means for operatively connecting such screw to such levers, substantially as described.

5. In a loose-leaf binder, the combination of 125 a pair of side binder-frames provided with binder-pins extending therebetween, a pair of crossed levers pivotally connected together at their longitudinal center each having one end pivotally connected with each side binder- 130

frame, an operating-screw mounted between such side binder-frames, and screw-engaging mechanism pivotally connected with such crossed levers and in threaded engagement 5 with such screw, substantially as described.

6. In a loose-leaf binder, the combination of side binder-frames, lever mechanism connected with such side binder-frames, a pair of studs pivotally mounted upon oppositely-movable portions of such lever mechanism and provided with perforations for receiving a screw, and a screw mounted in such pivoted studs and extending at right angles with relation to the side binder-frames for operating 5 such levers and thereby the side binder-frames, substantially as described.

7. In a loose-leaf binder, the combination of side binder-frames, lever mechanism connected with such side binder-frames, a pair of studs each provided with a threaded perforation therein and pivotally mounted upon adjacent oppositely-movable portions of such lever mechanism, and a screw provided with right and left screw-threads upon its opposite 5 ends, respectively, in threaded engagement with such pivoted studs, substantially as described.

8. In a loose-leaf binder, the combination of side binder-frames, a pair of levers pivotally connected together each having one end connected with each side binder-frame, a pair of studs each pivotally mounted upon a separate lever at equal distances from the point at which such levers are pivotally connected and 5 provided with threaded perforations having right and left screw-threads, respectively, and a screw provided with right and left screw-threads in threaded engagement with such pivoted studs, respectively, for operating the levers and thereby the side binder-frames, substantially as described.

9. In a loose-leaf binder, the combination of a pair of side binder-frames, a pair of levers pivotally connected together each having one 5 end connected with each side binder-frame, a pair of studs each pivotally mounted upon a separate lever at equal distances from the point at which such levers are pivotally connected together and provided with threaded perforations having right and left screw-threads, respectively, a screw provided with right and left screw-threads in threaded engagement with such pivoted studs, respectively, for operating the levers and thereby the side binder-frames, and telescopic guides formed of tubes attached to one of such side binder-frames and pins attached to the other side binder-frame and extending slidably into the axial openings of such tubes, substantially as described.

10. In a loose-leaf binder, the combination of side binder-frames, a pair of levers pivotally connected together each having one end connected with each side binder-frame, a pair of studs each pivotally mounted upon a separate 5 lever at equal distance from the point at which

such levers are pivotally connected and provided with threaded perforations having right and left screw-threads, respectively, a screw provided with right and left screw-threads in threaded engagement with such pivoted studs, 70 respectively, for operating the levers and thereby the side binder-frames, and a back formed of two relatively movable portions each connected with one of such side binder-frames and extending in the direction of the 75 opposite side binder-frame, substantially as described.

11. In a loose-leaf binder, the combination of side binder-frames provided with binder-pin mechanism mounted thereon, a pair of levers pivotally connected together at their longitudinal center and pivotally connected at their swinging ends with such side binder-frames, a pair of studs each pivotally mounted upon one of such levers and provided with 80 right and left screw-threaded perforations, respectively, a screw provided with right and left screw-threads upon its opposite ends mounted in threaded engagement with such studs and extending at right angles to the side 85 frames, a pair of separately-movable back portions each connected with one of such side binder-frames, and a pair of side cover-leaves each flexibly connected with a side binder-frame, substantially as described. 90

12. In a loose-leaf binder, the combination of a pair of side binder-frames provided with binder-pin mechanism mounted thereon, a pair of levers pivotally connected together at their longitudinal center and pivotally connected at 95 their swinging ends with such side binder-frames, a pair of studs each pivotally mounted upon one of such levers and provided with right and left screw-threaded perforations respectively, a screw provided with right and left screw-threads upon its opposite ends mounted in threaded engagement with such 100 studs and extending at right angles to the side frames, a pair of separately-movable back portions each connected with one of such side binder-frames, and a pair of side cover-leaves each provided with a flexible covering having 105 an inner lap attached to the inner side of one of such side binder-frames and an outer lap extending around the outside of the side 110 binder-frame and the back portion mounted thereon, substantially as described. 115

13. In a loose-leaf binder, the combination of side binder-frames, lever mechanism connected with such side binder-frames, a plurality of studs each pivotally mounted upon one of such levers, and a screw rotatably mounted in such pivoted studs for operating such levers and thereby the side binder-frames, substantially as described. 120
